US00D748296S

(12) **United States Design Patent**
Reier et al.

(10) **Patent No.:** US D748,296 S
(45) **Date of Patent:** ** Jan. 26, 2016

(54) **LED LAMP**

- (71) Applicant: **Cree, Inc.**, Durham, NC (US)
(72) Inventors: **Bart P. Reier**, Cary, NC (US); **Curt Progl**, Raleigh, NC (US); **Mark Edmond**, Raleigh, NC (US)
(73) Assignee: **Cree, Inc.**, Durham, NC (US)
(***) Term: **14 Years**
(21) Appl. No.: **29/484,541**
(22) Filed: **Mar. 11, 2014**

Related U.S. Application Data

- (63) Continuation-in-part of application No. 13/803,841, filed on Mar. 14, 2013, now Pat. No. 9,052,093.

(57) **CLAIM**

We claim the ornamental design for a LED lamp, as shown and described.

DESCRIPTION

FIG. 1 is a front view showing an embodiment of our new design for a LED lamp;

FIG. 2 is a right side view showing our new design shown in FIG. 1;

FIG. 3 is a left side view showing our new design shown in FIG. 1;

FIG. 4 is a back view showing our new design shown in FIG. 1;

FIG. 5 is a top view showing our new design shown in FIG. 1; FIG. 6 is a bottom view showing our new design shown in FIG. 1;

FIG. 7 is a top perspective view showing our new design shown in FIG. 1; and,

FIG. 8 is a bottom perspective view showing our new design shown in FIG. 1.

The broken lines in the drawings illustrate portions of a LED Lamp which form no part of the claimed design.

1 Claim, 7 Drawing Sheets
